VENT HEAD

Filed Dec. 8, 1930

UNITED STATES PATENT OFFICE

CHARLES F. MYERS, OF BALTIMORE, MARYLAND

VENT HEAD

Application filed December 8, 1930. Serial No. 500,971.

My invention relates to means for protecting the vents of containers holding inflammable liquids and has particular reference to a vent head applicable to the vent pipes 5 of such containers.

An important object of the invention is the provision of a vent head provided with means for preventing the entrance of rain and dirt to the interior of the container with 10 which it is associated and having also means to check fire at the vent head.

Another object of the invention is the provision of a vent head having a readily detachable screen element associated with the 15 opening thereof.

A further object of the invention is the provision of a vent head formed as a unitary casting and provided with a readily detachable screen covering the vent aperture.

20 With these and such objects in view as will be apparent from the description, the invention resides in the combination, construction and arrangement of parts hereinafter described and claimed and illustrated in the 25 accompanying drawings, in which:

Figure 1 is a perspective of a vent head constructed in accordance with the principles of the invention.

Figure 2 is a bottom plan view thereof.

30 Figure 3 is a section taken on the line 3—3 of Figure 2.

Figure 4 is a section on the line 4—4 of Figure 3.

Figure 5 is a perspective of a screen holding frame employed in connection with the 25 vent aperture of the device.

In detail the invention comprises a unitary casting in the form of a cowl shaped member 10 having a neck 11 internally threaded 40 for engagement over the upper end of a vent pipe and formed with a laterally extending hood 12 which is enlarged with respect to the diameter of the neck 11. The hood 12 is formed with a depending edge flange 13 which extends below the upper end of the neck portion 11 as defined by its internal wall 14.

A single narrow web 15 integrally unites 50 the neck wall 14 with the interior of the hood 12 at a point spaced appreciably above the

rim or edge flange 13. In the plane of the bridge web 15 the interior wall of the hood portion 12 is formed with a continuous lateral shoulder 16 which cooperates with the bridge 15 to provide a seat for a screen 17 which completely covers the vent aperture through the casting.

The protective screen 17 is retained in place by the clamping engagement thereover of a frame 18 having the configuration of the shoulder 16 and provided with a bridge portion 19 adapted to overlie the web 15 of the casting. The frame is retained in place by suitable means such as a screw bolt 20 headed against the frame bridge 19 and embedded in the casting web 15. It is obvious that as the screw bolt 20 is advanced the frame 18 will be clamped against the screen 17 holding the same firmly against its seat within the hood 12 and completely covering the vent aperture.

It will be apparent by the construction illustrated that the protective hood 12 prevents the entry of rain or dirt to the neck 11 and by reason of its depending edge flange 13 the protective screen member 17 is positioned at one side of and beneath the top of the neck 11. The casting is so shaped that the securing element 20 is readily accessible at all times for replacement of the screen whenever necessary. The screen member 17 is retained in position by a positive clamping means and does not depend upon frictional engagement for retention. Due to the fact that the retaining frame 18 is positioned from the under side of the web 15 it is apparent that when the frame 18 is removed, the screen 17 is readily removable by a simple downward pull, or it may be dropped away as the retaining frame is removed. Accordingly a 85 replacement of the protective screen may be effected without removing the vent head from its attachment on a vent pipe.

While in this embodiment I have illustrated and described certain structural details, it is intended that various modifications may be made in such details as will fall within the scope of the invention as claimed.

I claim:

1. A vent head comprising a unitary cast-

ing having a neck adapted for threaded engagement over a vent pipe, a hood extending laterally from said neck and open from its under face, a shoulder formed on the inner 5 face of said hood above the bottom edge thereof, a screen seated against said shoulder, and screw means accessible from the under face of the hood for retaining said screen in service position.

10 2. A vent head comprising a unitary casting having a neck adapted for engagement over a vent pipe, a hood portion extending laterally from said neck portion and open at its bottom edge beneath the top of said 15 neck portion, a shoulder in said bottom edge, a screen positioned in and covering the open bottom of said hood, and means detachably engageable with said shoulder through said screen for clamping said screen in service 20 position.

25 3. A venting closure for vapors arising from combustible material, comprising a fitting having a downwardly extending opening provided with fastening means, and venting through the downwardly facing opening, a screen removable downwardly from said venting opening, said opening being provided with an interior shoulder against which said screen abuts, and fastening means 30 holding said screen against said shoulder and permitting the ready removal of said screen.

In testimony whereof I affix my signature.
CHARLES F. MYERS.
